Specification for Design.

Patented Feb. 7, 1922.

Application filed June 17, 1921. Serial No. 478,450. Term of patent 14 years.

To all whom it may concern:

Be it known that I, ANDREW J. SANFORD, a citizen of the United States of America, residing at Newark, in the county of Licking and State of Ohio, have invented a new, original and ornamental Design for Pitchers, of which the following is a specification, reference being had to the accompanying drawing, forming part thereof.

In the form of the invention illustrated in the drawing the design is illustrated as

one complete example of the physical embodiment of the invention as a molasses can.

Figure 1 is a side view of the pitcher showing the design embodied therein.

Figure 2 is a view in rear elevation of the pitcher illustrated in Figure 1.

I claim:—

The ornamental design for a pitcher, as shown.

ANDREW J. SANFORD.
